2

By way of example, an embodiment of the invention is described hereinafter with reference to the accompanying drawings.

FIGURE 1 is a front elevation of a water closest cistern with part of its front wall cut away to reveal the hydraulic motor of a ventilator according to the invention.

FIGURE 2 is a partly sectioned side elevation of the ventilator and cistern of FIGURE 1.

The illustrated ventilator comprises an axial flow fan 1 disposed within a cylindrical fan casing 2, a turbine type hydraulic motor 3 disposed within a water closet cistern 4 and drive transmission means 6 connecting the motor 3 to the fan 1.

The fan, which may be a circular sheet metal disc 7 with radially directed slits extending from the periphery of the disc part-way towards the centre and with the metal between each pair of said slits twisted out of the plane of the disc 7 to constitute fan blades 8, and a mounting boss 9 secured to the centre of the disc 7.

20 The fan casing 2 is secured to, or is part of, a supporting frame 10 comprising a back plate 11 adapted to be secured to a water closet 12, stiffening edge flanges 13 and cistern supporting cantilevers 14 projecting from the back plate 11. The fan casing 2 is preferably provided with 2 sheet metal or other semi-circular weather flaps 15 that swing upon wire spindles 16 (of which there is one for each flap 15). The spindles 16 are inclined so that the flaps 15 tend to swing under the influence of gravity to a position in which they close the air passage-way defined by the casing 2. On the other hand, the flaps 15 may swing to an open position when the fan 1 is operating due to the effect of the air flow induced by the fan.

25 The drive transmission means 6 comprises a drive shaft 17 able to rotate in plastics or other bearing bushes 18 within an externally threaded supporting tube 19 secured to the back wall of the cistern 4 by means of an end flange 20 on one side of the wall and a clamping nut 21 on the other.

30 The motor 3 preferably comprises an open bottomed, sheet-metal turbine casing 30 clamped in place by the flange 20 and a Pelton wheel type turbine rotor mounted on one end of the shaft 17. The rotor comprises a central sheet metal disc 22 and a plurality of buckets 23.

35 The rotor is disposed so that a jet of water issuing from a nozzle 24 extending from an otherwise conventional float operated cistern inlet valve 25 impinges on the buckets 23 to cause the rotor, and therefore the fan 1, to spin whenever the cistern 4 is being filled with water.

40 For preference, the supporting frame 10 includes spacer blocks 26 so as to leave a substantial air gap between the back wall of the cistern 4 and the inner face of the wall 12 to allow an unimpeded flow of room air to the fan 1 for exhaust thereby. Air may also flow directly into the 45 casing through an opening 27 above the cistern 4, which opening is preferably covered by means of an ornamental woven wire or expanded metal grille 28 or the like.

50 It will be seen that the above described and illustrated embodiment of the invention provides a very simple and 55 readily installed water closet ventilator which makes use only of water which is subsequently to be used for flushing purposes.

55 According to other examples of the invention, the fan 60 may be mounted more remotely from the cistern than is illustrated, in which event, the drive connection between the hydraulic motor and the fan may be, by means of gear trains, drive shafts, endless chains or belts riding upon sprockets or pulleys, a so-called flexible drive shaft of the 65 kind having a pliable core rotating within a pliable tubular sheath or other conventional mechanical drive transmission devices.

ABSTRACT OF THE DISCLOSURE

A flushing cistern mounted with respect to a support wall by a support frame fixed to the wall and having cantilevers supporting the cistern spaced from the support wall. In a passage in the support wall, is a ventilator fan driven by a hydraulic motor located in the cistern to be driven by water issuing from an adjacent inlet nozzle. Operatively interconnecting the hydraulic motor and ventilating fan is a drive shaft housed in a tube fixed with respect to the back wall of the cistern by a flange overlying the inner wall surface of the cistern and a cooperating nut engaged on external threads on the tube and against the outer wall surface of the cistern. A casing for the hydraulic motor is secured against the cistern wall by the flange.

This invention relates to ventilators for water closets of the kind comprising a fan and hydraulic motor wherein the motor is driven by the water flowing into the closet cistern to refill the cistern after a flushing operation.

Hitherto, the ventilator fan and its hydraulic motor have been mounted as a unit on the wall of the water closet or in some other suitable position and the motor has been pipe-connected to the flushing cistern in such a way that water issuing from the cistern's normal inlet valve is fed to the motor and then exhausted from the motor into the cistern reservoir.

Although ventilators of the kind referred to above have been satisfactory in operation, they have not found as widespread acceptance as they might have, primarily because of the additional piping and plumbing work needed to supply water to and from the motor.

A further disadvantage is that external piping is unsightly and there is always the risk of water leakage from faulty joints and the like.

It has been proposed hitherto to overcome the above disadvantages by installing both the fan and the motor inside the cistern; but, in such cases, the efficiency of the ventilator, even though it draws air directly from the toilet bowl, is greatly reduced because of the necessarily small air passageways which then have to be employed.

With the foregoing in mind, the present invention was devised to provide water closet ventilators having a ventilating fan outside the cistern but which does not call for additional plumbing work for the installation of the cistern.

That object is achieved by providing a water closest ventilator wherein the hydraulic motor is within the cistern's reservoir and is drive connected to a fan disposed outside the cistern.

According to preferred embodiments of the invention a wall mounted fan casing is provided which is adapted not only to define an air passageway for the fan but also to support the cistern in a position permitting ready connection of the fan to the hydraulic motor within the cistern. Thus, having installed the fan casing, the work of installing the cistern is the same as, or even less than, that normally required.

The above-described and illustrated embodiment of the invention requires very little modification of a conventional cistern namely only the provision of a single hole in the back wall through which the supporting tube 19 may extend but according to other examples of the invention, modified cisterns are used to provide air passageways extending from the fan to the room to be ventilated. For example, the back wall of the cistern may have an open ended recess or trough extending from top to bottom or from side to side within which the fan may be disposed. According to another embodiment, a modified cistern is provided with a large tubular passageway extending from front to back through the water space and the fan may be mounted within that passageway, thus eliminating the need for a separate fan casing.

In some cases a main cistern may be used for the supply of water to a plurality of water closets and a single motor in said main cistern may then be drive-connected to a plurality of fans.

It will also be appreciated that the fan is not necessarily an axial flow fan and may be a centrifugal fan or indeed any mechanically driven ventilating device adapted to extract air from a room.

In short, the present invention extends to any hydraulically powered ventilator wherein a fan is disposed outside the cistern, and a hydraulic driving motor is disposed within the cistern irrespective of the precise disposition of those components.

I claim:

1. In combination with a water closet including a flushing cistern and a water inlet nozzle located in the cistern for refilling the cistern after flushing; a water closet ventilator assembly comprising in combination, a hydraulic motor disposed within the cistern in close proximity to the outlet of the inlet nozzle to be driven by water issuing from the inlet nozzle after a flushing operation, an exhaust fan disposed outside the cistern, a drive transmission means extending from said hydraulic motor to said exhaust fan to drive the fan during refilling of the cistern, said hydraulic motor including a rotor, said cistern having a wall including an aperture extending through the wall, said drive transmission means including a shaft extending through said aperture in said cistern wall and having one end connected to said rotor and another end connected to said fan, said hydraulic motor further including a casing having an aperture therein located about the aperture in the cistern wall, said drive transmission means further including a support tube extending through said aperture in said cistern wall with the support tube receiving said shaft, a flange means projecting from said tube internally of said hydraulic motor casing and engaging the hydraulic motor casing to maintain the hydraulic motor casing against the wall of the cistern, said support tube having external peripheral threads, and a locking nut threadedly engaged on the threads on the support tube and secured in engagement with the outside surface of the cistern wall to act together with said flange means to secure the tube and shaft in position.

2. The combination defined in claim 1 further including a support wall spaced from said cistern wall and having an exhaust opening receiving the exhaust fan, a support frame fixed to the support wall and located between the support wall and the cistern, cantilever means projecting from the frame below the cistern to support the cistern.

3. The combination defined in claim 2 further including

spacer means located between the support frame and said cistern wall to space the cistern from the support frame a predetermined distance.

4. The combination defined in claim 3 wherein said support frame is a flat plate including stiffening flanges projecting from the opposite side edges thereof.

5. In combination with a water closet including a flushing cistern and a water inlet nozzle located in the cistern for refilling the cistern after flushing; a water closet ventilator assembly comprising in combination, a hydraulic motor disposed within the cistern in close proximity to the outlet of the inlet nozzle to be driven by water issuing from the inlet nozzle after a flushing operation, an exhaust fan disposed outside the cistern, a drive transmission means extending from said hydraulic motor to said exhaust fan to drive the fan during refilling of the cistern, a support wall having an exhaust opening receiving the exhaust fan, a support frame fixed to said support wall between the cistern and the support wall, said support frame having

10 cantilever means projecting therefrom under said cistern to support said cistern, and spacer means spacing said cistern and said support frame to allow multi-directional air flow around, over the cistern and into the exhaust opening in the support wall for ventilation.

6. In combination with a water closet including a flushing cistern and a water inlet nozzle located in the cistern for refilling the cistern after flushing; a water closet ventilator assembly comprising in combination, a hydraulic motor disposed within the cistern in close proximity to

20 the outlet of the inlet nozzle to be driven by water issuing from the inlet nozzle after a flushing operation, an exhaust fan disposed outside the cistern, drive transmission means extending from said hydraulic motor to said exhaust fan to drive the fan during refilling of the cistern, a support

25 wall having an exhaust opening receiving said exhaust fan, a support frame fixed to said support wall and having means supporting said cistern, said cistern having a back wall including an opening, said drive transmission means including a support tube extending through said opening in

30 said back wall of the cistern, a drive shaft rotatably mounted in said support tube and having one end operatively connected to the hydraulic motor and an opposite end operatively connected to said exhaust fan to drive the fan in response to movement of said hydraulic motor.

35 7. The combination defined in claim 6 further including spacer means positioned between said back wall of the cistern and said support frame for spacing the cistern from the support frame to provide multidirectional air flow around, over and under the cistern and ultimately into the exhaust opening of the support wall for ventilation.
